Edgar Dale & S.

UNITED STATES PATENT OFFICE.

CHARLES J. SOSS, OF NEW YORK, N. Y., ASSIGNOR OF ONE-THIRD TO HENRY SOSS AND ONE-THIRD TO SAMUEL SOSS, BOTH OF NEW YORK, N. Y.

HINGE AND METHOD OF MAKING THE SAME.

1,319,427.

Specification of Letters Patent.

Patented Oct. 21, 1919.

Application filed September 28, 1918. Serial No. 256,022.

To all whom it may concern:

Be it known that I, CHARLES J. Soss, a citizen of the United States, and residing at New York, in the county of New York and State of New York, have invented certain new and useful Improvements in Hinges and Methods of Making the Same, of which the following is a specification, such as will enable those skilled in the art to which it applies to make and use the same.

This invention relates to hinges and particularly to what are known as invisible hinges, and the invention consists in an improved method of making the movable or swinging part of such hinges, and particularly such part as shown and described in United States Letters Patent No. 1,078,703 granted to Charles J. Soss and Henry Soss, November 18, 1913; and the object thereof is to so form the swinging or movable part or arm of a hinge as to reduce the cost of manufacture as well as to produce a stronger part; and with this and other objects in view the invention consists in the improved method herein shown, described and claimed.

The invention is fully disclosed in the following specification, of which the accompanying drawing forms a part, in which the separate parts of my improvement are designated by suitable reference characters in each of the views, and in which:—

Figure 1 is a front view of a hinge made according to my invention and showing the hinge butt and the movable part or arm;

Fig. 2 a transverse sectional view on the line 2—2 of Fig. 1;

Fig. 3 a plan view of a blank from which the movable part or arm is made;

Fig. 4 a section on the line 4—4 of Fig. 3 showing the first step in forming my improved arm;

Fig. 5 a view similar to Fig. 4 showing the second step in the formation of said arm;

Fig. 6 a plan view showing the arm completely formed;

Fig. 7 a view similar to Fig. 3 but showing only a part of the construction and showing a modification;

Fig. 8 a section on the line 8—8 of Fig. 6 but showing the modification shown in Fig. 7; and,

Fig. 9 a section on the line 9—9 of Fig. 6 and showing another modification.

In Figs. 1 and 2 of the drawing, I have

indicated at 10 that part of the hinge which is secured to the door frame, or what is commonly known as the hinge butt, and at 11 a part or arm secured to the door. The part 10 may be of the usual or any preferred form and construction and as shown consists of a backwardly directed hollow box-shaped portion 12 having a front flange portion 13 provided with a central opening 14. The part or arm 11 is mounted on a pin 15 secured in the part 10, or a member 16 detachably connected therewith.

The part 10 and the details of construction thereof as shown and above described forms no part of this invention but is merely shown and described to illustrate one form of hinge or hinge butt with which the part or arm 11 which is the basis of this application may be connected.

In the practice of my invention, or in the formation of the part or arm 11, I cut from a suitable sheet of metal, a blank 17 such as shown in Fig. 3 of the drawing, said blank consisting of an elongated central shank or body portion 18 at the ends of which are oblong cross heads 19 and 20. In forming the part 11 from the blank 17, I first depress one end portion of the body 18 adjacent to the cross head 19 as shown at 21 in Fig. 4, and the opposite end portion of said body part as well as the central portion of the cross head 20, as shown at 22, said depressions being of the general form shown in Fig. 4 and being made in opposite directions.

In the next step in forming the part 11, I bring the separate cross heads 19 and 20, or the faces 23 and 24 thereof together as shown in Fig. 5 and form a bead or cylindrical bearing portion 25 centrally of the body portion 18 of the blank.

After the separate end portions of the blank 17 have been brought together and formed as shown in Fig. 5, the same are fashioned to form a hook-shaped arm 26 as shown in Fig. 6 of the drawing, and when said blank is in the form shown in said figure, the separate abutting parts thereof may be secured together by welding, brazing, riveting or otherwise in the usual or any desired manner, after which said part or arm may be given the finishing operation, such as the drilling of countersunk screw holes 27 in the opposite sides of the cross heads 19 and 20, and the rounding of the

edge or corner portions of the body 18 in its folded position. The part 11 may then be connected with the part 10 of the hinge in the manner above set out as will be readily understood.

It will be noted on consideration of Figs. 2, 4, 5 and 6 of the drawing that by forming depressions 21 and 22 in the opposite end portions of the body 18 and in the cross head 20 of the blank 17 and folding said blank and bending it in the manner shown, the part or arm 11 is reinforced or strengthened at the point 28, or where the body part 18 joins the cross heads 19 and 20, and this method of constructing the part 11 of the hinge produces not only a simple and economical part but one of great strength.

In Figs. 7 and 8 of the drawing, I have shown a slight modification which consists in providing oppositely projecting flanges 29 on the body part 18 of the blank 17 adjacent to the head end 19 thereof, which flanges are adapted to be bent over the opposite side portion of said body part as shown at 30 in Fig. 8 of the drawing in the formation of the part or arm 11, and these flanges serve to strengthen the body part 18 as well as to finish the opposite edges thereof.

In Fig. 9 of the drawing, I have shown another modification which consists in providing the body portion 18, or the separate parts thereof, when in their fashioned position, as shown in Fig. 6 with a rib or corrugation 31, which will extend from the point 32 to the point 33 in Fig. 6 of the drawing, and said rib or corrugation is indicated in dotted lines in said figure.

As will be seen, my improved method of forming the part 11 consists simply in providing a suitable blank forming depressions at the opposite end portions thereof to reinforce and strengthen the same, bending the blank approximately centrally thereof to form a bead or cylindrical bearing member, fashioning the parts thus connected to the desired form and securing the same together by welding, riveting, brazing or otherwise, and while I have shown certain details of construction for carrying my invention into effect, it will be understood that various changes in and modifications of these details may be made, within the scope of the appended claims, without departing from the spirit of my invention or sacrificing its advantages.

Having fully described my invention, what I claim as new and desire to secure by Letters Patent, is:—

1. The method herein described for forming the swinging member of a hinge from sheet metal which consists in providing an elongated blank comprising a central shank or body portion provided at its ends with transverse cross heads, folding said blank to bring said cross heads together at one end

and to form of said blank an arm provided at the opposite end with a transverse cylindrical bearing, and securing the separate parts of the arm thus formed and the cross heads together.

2. The method herein described for forming the swinging member of a hinge from sheet metal which consists in providing an elongated blank comprising a central shank or body portion provided at its ends with transverse cross heads, forming depressions in the opposite end portions of the shank or body portion one of which extends into the corresponding cross head, folding said blank to bring said cross heads together at one end and to form of said blank an arm provided at the opposite end with a transverse cylindrical bearing, giving said arm the desired shape and securing the separate parts of the arm thus formed and the cross heads together.

3. The method herein described for forming the swinging member of a hinge from sheet metal which consists in providing an elongated blank comprising a central shank or body portion having at its ends transverse cross heads, forming depressions in the opposite end portions of the shank or body portion one of which extends into the corresponding cross head, providing the shank or body portion adjacent to one of the cross heads with oppositely directed flanges, folding said blank to bring said cross heads together at one end and to form of said blank an arm provided at the opposite end with a transverse cylindrical bearing, giving said arm the desired shape, and securing the separate parts of the arm thus formed and the cross heads together and folding the oppositely directed flanges at one end of the shank or body portion around the other part thereof.

4. A swinging hinge member formed from an elongated blank of sheet metal provided at its ends with cross head members and folded to bring the cross head members together and to form an arm provided at one end with a two-part cross head and at the opposite end with a transverse cylindrical bearing, the parts of said arm and of said two-part cross head being secured together.

5. A swinging hinge member formed from an elongated blank of sheet metal provided at its ends with cross head members and folded to bring the cross head members together and to form an arm provided at one end with a two-part cross head and at the opposite end with a transverse cylindrical bearing, the parts of said arm and said two-part cross head being secured together, and means for reinforcing said hinge member where the arm joins the two-part cross head.

6. A swinging hinge member formed from a suitable sheet metal blank, said hinge

member comprising an arm portion at one end of which is a cylindrical bearing and at the opposite end of which is a cross head, said arm and said cross head being composed of a plurality of thicknesses of metal secured together to form said hinge member, and means for reinforcing said hinge member where the arm joins the cross head.

7. A swinging hinge member formed from a suitable sheet metal blank, said hinge member comprising an arm portion at one end of which is a cylindrical bearing and at the opposite end of which is a cross head, said arm and said cross head being composed of a plurality of thicknesses of metal secured together to form said hinge member, means for reinforcing said hinge member where the arm joins the cross head, and means for reinforcing said arm between the cross head and the cylindrical bearing.

8. A swinging hinge member comprising an approximately hook-shaped arm provided at one end with a two-part attaching member and at the opposite end with a cylindrical bearing, said arm and its attaching member being formed from a single strip of metal.

9. A swinging hinge member comprising an approximately hook-shaped arm provided at one end with a single two-part head and at the opposite end with a cylindrical bearing, said arm and said head being

formed of a plurality of thicknesses of metal secured together.

10. The method herein described of forming a swinging arm for a hinge from sheet metal which consists in providing an elongated blank comprising a central shank or body portion provided at its ends with attaching parts, and folding said blank to bring said parts together at one end to form a single attaching member composed of two parts and to form from said blank said swinging arm provided at one end with a transverse cylindrical bearing and at the opposite end with said two-part attaching member.

11. A swinging arm for hinges formed from an elongated blank of sheet metal provided at its ends with attaching head members and folded to bring said head members together and to form a single attaching head composed of two parts and to form an arm provided at one end with a cylindrical bearing and at the opposite end with said attaching head.

In testimony that I claim the foregoing as my invention I have signed my name in presence of the subscribing witnesses this 27th day of Sept. 1918.

CHARLES J. SOSS.
